HOOK FOR FORMING SLIP HITCHES IN
CABLES OR THE LIKELeslie G. Ehmann, Portland, Oreg., assignor to
Electric Steel Foundry, Portland, Oreg., a cor-
poration of Oregon

Application July 5, 1947, Serial No. 759,285

10 Claims. (Cl. 294—74)

1

This invention relates to hooks for forming slip hitches in cables or the like as, for instance, in guy lines of a type adapted to use in the logging industry and the like.

Although in general appearance and some aspects the structure of the disclosed hook is quite similar to those hooks known as "choker hooks," the two types of hooks are adapted to different uses and to use under different conditions. Thus, the differences of structure between the two types of hooks are important in adapting each to its intended use and type of service.

For example, and by way of comparison, both types of hooks are used with a cable having a ferrule on the end thereof, which ferrule connects with the hook to form a slip loop in the cable. However, the choker hooks are generally used on the ground, as, for instance, in the formation of hitches for dragging logs. In such service, and to avoid their loss when not in use, they are semi-permanently attached to the cable, in that they will not slip off of the cable over the ferrule. On the other hand, the presently disclosed hooks are adapted to such uses as the making of hitches for the connection of guy line cables to a spar tree. Such hitches are made high on the spar tree by a man, known as a "high climber," who must hold onto the tree while making the hitch. For this service, and for greater ease of handling, the hook is desirably removable from the cable over the ferrule and readily placeable thereon. It is also important that when the hook is placed upon the cable, it will assume its proper and operative position relative to the spar tree without the exertion of manual effort on the part of the high climber and without the formation of kinks in the cable.

From the foregoing discussion it may be readily understood that it is a general object of this invention to provide a hook particularly suited to use in the formation of slip hitches in cables, guy lines and the like and at places in which the user is working under handicaps.

As another object my invention comprehends the provision of a hook for use with a cable having a ferrule at the end and which may be readily placed upon and removed from the cable without removal of the ferrule.

My present invention further has within its purview the provision of a guy line hook adapted to be threaded onto a ferruled cable, guy line or the like and so constructed and arranged that it will effectively and readily assume its proper operational position without kinking the cable.

Another object of the invention is to provide a

2

hook adapted easily to be threaded onto a cable from either of two sides and, in either instance, to assume a proper operating position when the end of the cable is connected thereto and the cable is tightened.

It is a further object of this invention to provide a guy line hook adapted to the formation of a cable hitch and so constructed that it may be threaded onto a ferruled guy line cable and properly connected thereto for the formation of a slip loop extending around a spar tree in either direction.

Other objects and advantages of the invention will be apparent from the following description and the accompanying drawings in which similar characters of reference indicate similar parts throughout the several views.

In the two sheets of drawings:

Fig. 1 is a fragmentary perspective view depicting the application of a preferred form of my hook to the formation of a slip noose on a spar tree or the like for securing the end of a guy line;

Figs. 2 and 3 are perspective views taken substantially from opposite sides of the hook shown in Fig. 1 and wherein cable threading and operating positions relative to the hook are indicated fragmentarily in solid and dot and dash lines;

Figs. 4 and 5 are, respectively, front and side elevational views of the guy line hook shown in Figs. 1 to 3; and

Fig. 6 is an end sectional view wherein the section is taken substantially on a line 6—6 of Fig. 4 and viewed in the direction indicated by the accompanying arrows.

The hook disclosed for illustrative purposes in the accompanying drawings is one well suited for use by high climbers in the attachment of guy lines to spar trees. For such and other uses and in order to avoid the necessity of eye splices in the cables, the disclosed hook is adapted to ready separation from and application to a cable having an enlarged fastening element, such as a ferrule secured to the end thereof at which the slip noose is to be formed in the cable.

As depicted in the various views in the accompanying drawings, my preferred form of hook has an elongated metallic body 10 which is desirably cast in one piece. The general contour of the body 10 is irregular and unsymmetrical about any one line or plane, although it may be considered for reference purposes to have a central longitudinal axis, as indicated by the line 12 in Figs. 4 and 5.

An opening, designated generally by the reference numeral 13, extends laterally through the

body 10 in varying directions transverse to the body and the longitudinal axis thereof. In one respect, the opening 13 has the general contour of an open slot extended longitudinally of the body and along the central axis with contours effectively of a shape formed by the gradual twisting thereof about the central axis to the extent that the opposite ends are preferably disposed in substantially right angular relationship to one another. In its general position relative to the body 10, the opening 13 is considerably closer to one end thereof than to the other.

Considered in another aspect, the opening 13 includes at one end thereof a through passage 14 located in the mid-portion of the body 10 and extending therethrough in one direction and transversely of the longitudinal axis. Adjacent one end of the body and extending therethrough in a direction transverse to the through passage 14, as well as to the longitudinal axis 12, the opening 13 forms a slip-sleeve 15. The through passage 14 is adapted to use as a cable-threading opening and is, consequently, of a size sufficient freely and readily to pass around a fastening element such as a ferrule 16 secured to the end of a cable 17 or the like, as shown in Figs. 2 and 3. The slip-sleeve 15, on the other hand, is, by preference, smaller than the through passage 14 to an extent that the cable 17 will slide therethrough with relative freedom, but the ferrule 16 will not pass therethrough.

Intermediate the through passage and slip-sleeve portions 14 and 15, respectively, the opening 13 is of sufficient size to pass the cable 17 and opposed body surfaces 18 and 19 which partially define the complete opening 13 are smoothly curved to effect a gradual turning movement of the hook body relative to the cable 17 as the cable passes from the through passage 14 to the slip-sleeve 15. In addition to the smoothly curved inner surfaces 18 and 19, the opening 13 is partially defined at oppositely disposed edges by smoothly curved and preferably rounded edge surfaces 20 and 22, which edge surfaces are shaped cooperatively to assist and merge with the opposed inner surfaces and to coact with the cable 17 for effecting the turning movement of the hook body as the cable passes longitudinally of the opening 13 from the threading passage to the slip-sleeve.

In addition to being disposed in a direction lateral to the through passage 14, the slip-sleeve 15 desirably has its opposite end portions curved in a direction extending along the longitudinal axis 12 and away from the major portion of the body and through passage 14. Thus, the slip-sleeve is curved and flared outwardly to follow somewhat the natural curvature of the cable in use and so as to avoid binding and the formation of sharp bends in the cable as it is drawn tight. In order to avoid the use of excessive metal and the resultant additional weight, the end 23 of the body is bowed to follow the curvature of the slip-sleeve. In addition to the aforementioned curvature, it is also my preference that the body 10 flare outwardly somewhat at opposite sides 24 and 25 to increase the total length of the slip-sleeve because in many instances, and as depicted in Fig. 1, the cable engages only one end portion of the slip-sleeve at a time.

From the foregoing description of the opening 13, through passage 14, and slip-sleeve 15, it may be readily understood that the cable 17 with the ferrule 16 attached thereto may be threaded through the through passage 14 in either direc-

tion, one direction of threading being depicted in solid lines in Fig. 2, and the other direction of threading being indicated in dot and dash lines at 16a and 17a in Fig. 3. In either instance the movement of the cable longitudinally of the body through the opening 13 effects a turning movement of the hook body until the hook reaches a position in which the cable passes through the slip-sleeve as depicted in solid lines in Fig. 3 and in dot and dash lines at 17a in Fig. 2. It may be further understood that when the cable is initially threaded through the through passage 14 in one direction, a slip-noose formed by putting the cable around a spar tree or the like in one direction will result in the hook being suspended in the same direction as when the initial threading of the cable through the through passages in the opposite direction and the cable is put around the tree the other way.

20 In order to effect the formation of a slip-noose in the cable, it is necessary to anchor the end of the cable to a complementary end of the hook after the cable is threaded into the slip-sleeve. For this purpose, and when fastening means such as the ferrule 16 is secured to the end of the cable 16, I prefer to provide a ferrule-receiving socket 26 in the end of the body 10 opposite the slip-sleeve 15 and adjacent the through passage 14. Also, by preference, the socket 26 is substantially 30 cylindrical with an axis substantially parallel to and somewhat offset to one side of the hook to the longitudinal axis 12, and has a ferrule-retaining end shoulder surface 27 at the end thereof opposite the through passage 14. The socket 26 35 opens into the through passage 14 on the side thereof opposite the slip-sleeve.

At the side of the socket 26 toward which the axis thereof is preferably displaced from the longitudinal central axis 12 of the hook, an axially 40 extending slot 28 opens into the socket and extends through a lower end portion 29 of the hook body to pass and accommodate the cable when the ferrule is disposed in the socket with the cable extending outwardly in an axial direction therefrom. The axial slot 28 opens into the through passage 14, and although it is of sufficient size for the cable to be passed therethrough, it is narrower than the ferrule so that when the ferrule is disposed in the socket in the position shown 50 in Fig. 3, it is normally and releasably held in that position. The sizes and proportions of the through passage 14 and socket 26 are so related with the length and diameter of the ferrule 16 that when the cable is threaded through the 55 through passage in either direction, a retraction and axial tilting movement of the cable will result in the seating of the ferrule within the socket.

The disposition of the socket 26 at the end of the hook body remote from the slip-sleeve and 60 the necessary mass of metal at the socket end of the hook have a tendency to locate the center of gravity of the hook nearer the socket end thereof than to the slip-sleeve end. Consequently, when the hook is threaded onto a cable, 65 it has a normal tendency to assume a position as a result of the action of gravitational force in which the cable extends through the slip-sleeve end of the hook. Also, when the hook is swung around the slip-sleeve end for connection to the 70 ferruled cable end, as shown in Fig. 1, to form a noose about a spar tree, the normal tendency of the socket and of the hook is to fall downwardly. Hence, it is by preference that whether 75 the loop extends around the tree in one direction or the other, the hook should be initially

threaded onto the cable in a direction such that the slot 28 faces downwardly for receiving the ferruled end of the cable. This may be accomplished, as previously explained, by keeping the direction of the initial threading of the cable through the through passage 44 in a direction consistent with the direction in which the cable is placed around the tree for the formation of a loop.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States is:

1. A hook for forming slip hitches in a cable or the like and for use with a cable having a ferrule of larger diameter than the cable secured to one end thereof and comprising, in combination, a somewhat elongated metallic body having a central longitudinal axis, an opening of irregular shape extending through said body nearer one end thereof than the other and including a slip-sleeve portion at and extending across one end of the body and of a size smaller than the ferrule and large enough for the cable readily to slide through, said slip-sleeve portion being transverse to said longitudinal axis and curved longitudinally of the axis and away from the major portion of the body, said opening also including a through passage in the mid-portion of the body of a size larger than said ferrule and having an axis substantially normal to said longitudinal axis and to the slip-sleeve portion, said body having smoothly curved edges and surfaces adjoining and defining said opening, said body also having at the end opposite the slip-sleeve portion a socket portion slotted axially of the body at one side to pass the cable, said socket portion opening into said through passage axially of the body and being of a size to receive and retain said ferrule, and the curvatures of said edges and surfaces being such that when the hook is threaded onto the cable by passing the ferrule and cable through said through passage those edges and surfaces will effect a turning movement of the hook as the cable passes from the through passage to the slip-sleeve portion of said opening.

2. A hook for forming slip hitches in a cable or the like and for use with a cable having anchoring means larger than the diameter of the cable on one end thereof and comprising, in combination, an elongated metallic body having a central longitudinal axis, an opening of irregular shape extending through said body nearer one end thereof than the other and including a slip-sleeve portion at and extending across one end of the body and of a size smaller than the anchoring means and large enough for the cable readily to slide through, said slip-sleeve portion being transverse to said longitudinal axis and curved in a direction longitudinal to the axis and away from the major portion of the body, said opening also including a through passage in the mid-portion of the body of a size larger than the anchoring means and having an axis substantially normal to said longitudinal axis and to the slip-sleeve portion, said body having smoothly curved edges and surfaces adjoining and defining said opening, said body also having

at the end opposite the slip-sleeve portion means for releasably connecting the end of the cable to the body, and the curvatures of said edges and surfaces being such that when the hook is threaded onto the cable by passing the ferrule and cable through said through passage those edges and surfaces effect a turning movement of the hook as the cable passes from the through passage to the slip-sleeve portion of said opening.

3. In a hook for forming slip hitches in a cable or the like and for use with a cable having a ferrule secured to one end thereof, the combination comprising an elongated metallic body having a central longitudinal axis, an opening of irregular shape extending through said body nearer one end thereof than the other and including a slip-sleeve portion at and extending across one end of the body and of a size smaller than the ferrule and large enough for the cable readily to slide through, said slip-sleeve portion being transverse to said longitudinal axis and curved in a direction longitudinal to the axis and away from the major portion of the body, said opening also including a through passage in the mid-portion of the body of a size larger than said ferrule and having an axis substantially normal to said longitudinal axis and to the slip-sleeve portion, said body having smoothly curved edges and surfaces adjoining and defining said opening, and the curvatures of said edges and surfaces being such that when the hook is threaded onto the cable by passing the ferrule and cable through said through passage those edges and surfaces effect a turning movement of the hook as the cable passes from the through passage to the slip-sleeve portion of said opening.

4. A hook for forming slip hitches in a cable or the like and for use with a cable having a ferrule of larger diameter than the cable on one end thereof and comprising, in combination, a somewhat elongated metallic body having a central longitudinal axis, said body having an opening of irregular and smoothly curved contour extending laterally therethrough at a position nearer to one end than the other of the body, said opening being effectively in the shape of a slot elongated longitudinally of the body and gradually twisted from one end to the other about said longitudinal axis so that the two ends thereof are disposed in substantially right angular relationship to one another, one end of said slot being larger than the other, the larger end of the slot being of sufficient size for the ferrule to be passed therethrough, the smaller end of the slot being smaller than the ferrule and sufficiently large to form a slip-sleeve for the cable, the smaller end of the slot also being curved at each end in the direction of said longitudinal axis and away from the larger end of the slot, said body also having therein at the end opposite said slip-sleeve and adjacent the larger end of said slot a ferrule-retaining socket opening into the larger end of said slot and shaped to engage and hold the ferrule with the cable extending longitudinally of said longitudinal axis, and a longitudinal slot extending into said body at one side of the socket for the passage and accommodation of the cable when the ferrule is placed in and removed from said socket.

5. A hook for forming slip hitches in a cable or the like and for use with a cable having anchoring means larger than the diameter of the cable on one end thereof and comprising, in combination, an elongated metallic body having a longitudinal axis, said body having an opening of ir-

regular and smoothly curved contour extending laterally therethrough at a position nearer to one end than the other of the body, said opening being effectively in the shape of an elongated open slot gradually twisted from one end to the other about said longitudinal axis so that the two ends thereof are disposed in substantially right angular relationship to one another, one end of said slot being larger than the other, the larger end of the slot being of sufficient size for the anchoring means to be passed therethrough, the smaller end of the slot being smaller than the anchoring means and sufficiently large to form a slip-sleeve for the cable, the smaller end of the slot also being curved at each end in the direction of said longitudinal axis and away from the larger end of the slot, said body also having at the end opposite said slip-sleeve means for connecting with and releasably holding the anchoring means.

6. In a hook for forming slip hitches in a cable or the like, the combination comprising an elongated metallic body having a longitudinal axis, said body having an opening of irregular and smoothly curved contour extending laterally therethrough at a position nearer to one end than the other of the body, said opening being effectively in the shape of an elongated open slot gradually twisted from one end to the other about said longitudinal axis so that the two ends thereof are disposed in substantially right angular relationship to one another, one end of said slot being larger than the other, the smaller end of the slot providing a slip-sleeve for the cable, the smaller end of the slot also being curved at each end in the direction of said longitudinal axis and away from the other end of the slot, said body also having at the end opposite said slip-sleeve a relatively heavy portion tending normally to swing that end downwardly when the hook is placed on a cable which extends through said opening, thereby tending normally to effect the suspension of the hook from the slip-sleeve end, and means for anchoring the end of a cable to the heavy end portion of the hook.

7. In a hook for forming slip hitches in a cable or the like, the combination comprising an elongated metallic body having a longitudinal axis, said body having an opening of irregular and smoothly curved contour extending laterally therethrough at a position nearer to one end than the other of the body, said opening being effectively in the shape of an elongated open slot gradually twisted from one end to the other about said longitudinal axis so that the two ends thereof are disposed in angular relationship to one another, the end of the slot which is nearer the adjacent end of the body providing a slip-sleeve for the cable, and the last mentioned end of the slot also being curved at each end in the direction of said longitudinal axis and away from the other end of the slot.

8. In a hook for forming slip hitches in a cable or the like, the combination comprising an elongated metallic body having a longitudinal axis, an opening of irregular shape extending through said body nearer one end thereof than the other and including a slip-sleeve portion at and extending across one end of the body, said slip-sleeve portion being transverse to said longitudinal axis and curved longitudinally of the axis and away from the major portion of the body, said opening also including a through passage in the mid-portion of the body having an axis substantially normal to said longitudinal axis and to the slip-sleeve portion, said body having smoothly curved edges and surfaces adjoining and defining said opening, and said body also being flared outwardly between the through passage and the slip-sleeve portion so that the slip-sleeve portion is materially longer than the through passage.

9. In a hook for forming slip hitches in a cable or the like, the combination comprising a metallic body having therein in adjacent relationship a threading opening and a slip-sleeve disposed with axes in spaced and substantially right angular relationship to one another and together comprising a completely closed cable receiving loop, said slip-sleeve being smaller than the threading opening, said body being open and smoothly curved between the threading opening and slip-sleeve to provide curved edges and opposed surfaces so relatively disposed that the cable will pass therethrough in various positions varying angularly in transverse planes without binding and while said surfaces and edges cam the hook to a position for free sliding movement along the cable.

10. In a hook for forming slip hitches in a cable or the like, the combination comprising a metallic body having a longitudinal axis, said body having an opening of irregular and smoothly curved contour extending therethrough in a direction lateral to the longitudinal axis, said opening being effectively in the shape of an elongated open slot gradually twisted from one end to the other about said longitudinal axis so that the two ends thereof are disposed in angular relationship to one another, one end of the slot providing a slip-sleeve for the cable, and the last mentioned end of the slot also being curved at each of its ends in the direction of said longitudinal axis and away from the other end of the slot.
